UNITED STATES PATENT OFFICE.

GEORGE C. EULER, OF EDGEWATER HEIGHTS, NEW JERSEY, ASSIGNOR TO R. B. DAVIS COMPANY, OF HOBGKEN, NEW JERSEY, A CORPORATION OF NEW JERSEY.

CAN-MAKING MACHINE.

Application filed November 2, 1925. Serial No. 66,134.

My invention relates to can making machines and is particularly directed to a machine for attaching the bottoms to metal, preferably tin, cans, and at the same time 5 curling the edge of the metal forming the top of the can.

My invention will be better understood by reading the following description taken in connection with the accompanying drawings, 10 in which

Fig. 1 is a top plan view of a portion of the machine showing my invention applied thereto;

Fig. 2 is a side elevation of the portion of 15 the machine shown in Fig. 1; and

Fig. 3 is an end elevation of the curling chuck on a scale larger than shown in Figs. 1 and 2.

My invention consists in the addition of an 20 attachment to a standard can-forming machine, such as that known as a horizontal double-seamer, and the combination of elements resulting from such addition, the machine acting to perform the specific functions 25 of double-seaming the bottoms and curling the tops of the cans. In illustrating my invention I have shown only such parts of the standard machine as are necessary to illustrate the application of my improvements 30 thereto.

Referring to the drawings, the parts of the standard machine comprise a feeding wheel 1 mounted on a shaft 2 and having grooves or recesses 3 therein for feeding cans at intervals to the double-seaming and curling mechanism. The details of the double-seaming mechanism are not illustrated because per se they do not constitute any part of my invention. The double-seaming mechanism 40 constitutes two operating rolls 4 and 5. The roll 4 performs a certain part of the operation of double-seaming and the roll 5 completes such operation. The rolls 4 and 5 are carried by the frame of the machine and 45 are supported in suitable bearings therein. A shaft 6 is also supported by the frame of the machine and carries two cams 7 and 8. Fastened to the cam 7 is a rod 9, one end of which is pivotally connected with an arm 10 loosely mounted on the shaft 2. The arm 10 carries a pawl 11 which engages the teeth of the ratchet wheel 12 and rotates the shaft 2 and therewith the feed wheel 1 which delivers the cans to the double-seaming rolls.

The shaft 2 carries a gear 13 which meshes

with a gear 14 on a shaft 15. The gear 14 is frictionally connected with the shaft 15 by means of the fiber collars 16 and 17, the friction of which is controlled by a nut 18 screw-threaded onto the shaft 15, as shown in Fig. 60

1. Shaft 15 carries a curling chuck 19 and when the shaft 15 is rotated the chuck 19 rotates therewith.

The chuck 19 is composed of a frame 20 in which are mounted three members 21, each 65 carrying a grooved wheel 22 attached to rotate in the respective members 21. The grooves in the wheels 22 are arranged on a circle having a center at the center of the shaft 15. The diameter of this circle is equal 70 to that of the can to be curled, for a reason which will appear later. The members 21 are movably mounted in the frame 20 and have a neck portion 23 projecting through the frame 20 and a ring 24 is attached to 75 the necks 23, as shown in Fig. 1. Compression springs 25 are seated at one end in the frame 20 and have their other ends placed against the ring 24 tending to move the ring and the members 21 which are attached 80 thereto to the right, as viewed in Fig. 1. This action of the springs therefore is to remove the curling chuck from the open end of the can 26, as shown in Fig. 1. It therefore is necessary to provide means for moving the grooved wheels 22 into engagement 85 with the end of the can. This means comprises the cam 8 upon which rides a roller 27 attached to the end of an arm 28 which in turn is pivotally connected with a bell-crank 90 lever 29 through the adjustable link 30. The bell-crank 29 is pivoted at 31 and the end 32 thereof is bifurcated, each arm of which carries a roller 33. The rollers 33 engage the ring 24 and when the roller 27 rides upon a 95 portion of the cam 8 the grooved wheels 22 are moved into engagement with the edge of the can to curl the same.

During the double-seaming of the bottom of the can the can is rotated and because of 100 the friction gear 14 the shaft 15, together with the curling chuck, is rotated except when the means about to be described are effective. In order to properly curl the top of a can it is necessary to have a relative 105 rotary movement between the can and the grooved wheels 22. Since the can is rotated by the double-seamer, I have chosen to arrest the rotation of the chuck and permit the can to rotate in the grooved wheels 22 to perform 110

the curling operation. The means for arresting the rotation of the curling chuck comprises the cam 7, and arm 35 having a roller 36 engaging the cam 7. The arm 35 is rigidly attached to a rod 37 which carries a pawl 38 at the other end and which pawl 38 is adapted to engage ratchet teeth 39 on the frame 20 of the curling chuck. When the roller 36 engages the proper portion of the cam 7 the pawl 38 is thrown into engagement with a tooth 39 and the rotation of the curling chuck is arrested. The arresting of the rotation of the chuck is possible because of the frictional engagement between the gear 14 and the shaft 15. The rotation of the chuck is arrested for only a short time because it requires only one or two revolutions of the can to effect the curling of the top. The cam 7 is therefore so designed that the pawl 38 will be released from the teeth 39 immediately upon the completion of the curling operation, and by an inspection of Fig. 2 it will be noted that the raised portion 40 of the cam 7 is a very small part 25 of the periphery thereof.

In operation a can is fed by the wheel 1 into position for operation by the first seaming roll 4. It is then moved into position for the operation of the second seaming roll 30 and the cams 7 and 8 are so designed that near the end of the double-seaming operation the chuck having the curling rolls thereon is moved toward the end of the can while the can is rotating and the rotation of the 35 chuck is then arrested, whereupon the continued rotation of the can causes the edge of the metal to be curled, as above explained. The cams automatically release the curling rolls from the end of the can and permit 40 the same to again rotate until the next can is in position and ready for the curling operation.

All of the above operations take place 45 rapidly and are entirely automatic and the simplicity of the device enables a large production to be secured from the machine without any substantial wear upon any of the active parts, thus insuring a long life and the efficient operation of the machine.

50 I have illustrated the preferred form of my invention and the form which has been tried and found commercially satisfactory; and while I prefer the construction shown, I wish to be understood that I am not limited 55 to the exact arrangement, as many detail changes may be made without departing from the spirit of my invention.

I claim:

60 1. In a machine of the character described, the combination of means for feeding cans at intervals, means for rotating and double-seaming the bottoms of the cans, and power-operated means for simultaneously engaging the open ends of the cans to curl the edges 65 thereof.

2. In a machine of the character described, the combination of means for feeding cans at intervals, means for rotating the cans, means for double-seaming the bottoms of the cans, power-operated means for simultaneously engaging the open ends of the cans to assist in rotating the cans, and means for arresting said power-operated means to curl the edges of the cans. 70

3. In a machine of the character described, the combination of means for feeding cans at intervals, means for rotating the cans and double-seaming the bottoms thereof, and automatic power-operated means for simultaneously engaging and curling the open 80 ends of the cans. 75

4. In a machine of the character described, the combination of means for feeding cans at intervals, means for engaging and double-seaming the bottoms of the cans, power 85 cam operated means for automatically engaging the open ends of the cans and causing the metal thereof to be curled while the bottoms are being seamed. 80

5. In a machine of the character described, 90 the combination of means for feeding cans at intervals, means for engaging and double-seaming the bottoms of the cans, cam operated means for engaging the open ends of the cans and causing the metal thereof to be curled while the bottoms are being seamed, 95 and means automatically releasing said curling means to permit the cans to be discharged. 100

6. A curling chuck for cans, comprising a rotatable head, rotatable grooved members in the head, cam-actuated means for moving the grooved members along the axis of rotation of the chuck, and springs for moving the grooved members in the opposite direction. 105

7. In a machine of the character described, the combination of means for feeding cans at intervals, power-driven means for simultaneously engaging both ends of the can, one of said means acting to seam the bottom of the can, and means for arresting the rotation of the other means at intervals whereby that end of the can is 110 curled. 115

8. In a can machine, the combination of means for feeding cans at intervals, power-driven means for engaging both ends of the can and rotating the can, one of said means acting to double-seam the bottom of the can while it is being driven from both ends, and means for arresting the other power-driven means while the can is being rotated whereby the top of the can is curled. 120

9. In a can machine, the combination of means for automatically feeding cans at intervals, power-driven means engaging the bottoms of the cans for rotating the cans and double-seaming the bottoms thereof, friction power-driven means engaging the tops 125 130

of the cans and assisting in the rotation of the cans until the bottoms are substantially double-seamed, and means for arresting the rotation of the curling means whereby a relative movement is produced between the can and the curling means and the top of the can is thereby curled.

10. In a machine of the character described, the combination of means for feeding cans at intervals, power-driven means for simultaneously engaging both ends of the can, one of said means acting to seam the bottom of the can, means for arresting the rotation of the other means at intervals whereby that end of the can is curled, and means automatically releasing said curling means to permit the cans to be discharged.

11. In a can machine, the combination of means for feeding cans at intervals, power-driven means for engaging both ends of the can and rotating the can, one of said means acting to double-seam the bottom of the can

while it is being driven from both ends, means for arresting the other power-driven means while the can is being rotated whereby the top of the can is curled, and means automatically releasing said curling means to permit the cans to be discharged.

12. In a can machine, the combination of means for automatically feeding cans at intervals, power-driven means engaging the bottoms of the cans for rotating the cans and double-seaming the bottoms thereof, friction power-driven means engaging the tops of the cans and assisting in the rotation of the cans until the bottoms are substantially double-seamed, means for arresting the rotation of the curling means whereby a relative movement is produced between the can and the curling means and the top of the can is thereby curled, and means automatically releasing said curling means to permit the cans to be discharged.

GEORGE C. EULER.
